UNITED STATES PATENT OFFICE.

OTTO H. H. HEINS, OF EDGEWATER, NEW JERSEY.

ELECTRIC SWITCH.

1,094,562.

Specification of Letters Patent. Patented Apr. 28, 1914.

Application filed June 30, 1909. Serial No. 505,268.

To all whom it may concern:

Be it known that I, Otto H. H. Heins, citizen of the German Empire, residing at Valley Place, Edgewater, New Jersey, have invented certain new and useful Improvements in Electric Switches; and I do hereby declare the following to be a full, clear, and exact description of the invention, such as will enable others skilled in the art to which it appertains to make and use the same.

This invention has reference to ignition systems and electric switches therefor and relates particularly to the ignition in engines for driving motor vehicles which employ two spark plugs in each engine cylinder, one spark plug being connected with a battery and the other spark plug being connected with a magneto generator.

One object of the invention is to provide simple and efficient means whereby the operator of the vehicle may cut out either or both sets of spark plugs at will.

A further object of the invention is to provide means for breaking circuits and preventing the closing of the same by unauthorized persons or through accident.

A further object of the invention is to provide a device capable of accomplishing the desired results which will be of simple construction and arranged in compact form, whereby it may be easily manufactured and applied and will occupy very little space in or on the vehicle.

With these objects, and such other incidental objects as may hereinafter appear, in view, the invention consists in a switch plate and a removable key for operating the same, the switch plate being incapable of operation unless the key is in place and being necessarily in the circuit-breaking position when the key is removed.

The invention further consists in an arrangement of circuits and circuit-terminals and a construction of switch plate whereby the breaking or closing of the igniter circuits may be accomplished easily and at will.

The invention further consists in a peculiar frame or support by which the device may be quickly and securely fastened to the dashboard or other part of the vehicle, and finally the invention consists in certain novel details all of which are illustrated in the accompanying drawings and will be herein-after first fully described and then particularly pointed out in the appended claims.

In the said drawings, Figure 1, is a dia-

grammatic view of the switch in the zero position and connected through a battery and a magneto with the spark plugs; Fig. 2 is a central vertical section of the complete switch with the operating key in position therein; Fig. 3 is a view from the rear of the switch with the back removed; Fig. 4 is a detail longitudinal section of the switch plate; Fig. 5 is a detail section of the main supporting plate; Fig. 6 is a front elevation of the device with the key removed; Fig. 7 is a detail view of the key; Figs. 8 and 9 are diagrammatic views showing different positions of the switch; Fig. 10 is a detail elevation of the switch plate; Fig. 11, a rear elevation of the complete switch, and Fig. 12, a detail view partly in section, of a modification of the switch in which the key is provided with a plurality of wards.

In carrying out this invention, I employ a main support consisting of a circular plate, 1, having an integral central sleeve or bearing, 2, projecting forward therefrom and provided with a plurality of rearwardly projecting collars or tubes, 3, as clearly shown. The front end of the bearing, 2, presents a central circular opening, 4, and diametrically opposite open-ended slots, 5, leading radially therefrom. For convenience of manufacture, the front end of the bearing is provided with an annular shoulder, 6, in which is seated a ring or collar, 7, the end of the bearing being crimped over the ring to secure it in place. The inner annular face of the ring is shaped to provide the opening 4 and the slots 5, and its outer circumferential face may be corrugated or roughened to prevent shifting of the same annularly upon its seat in the end of the bearing. The switch plate comprises a metallic disk, 8, having a central forwardly projecting key-pipe, 9, which will fit snugly but turn readily in the bearing 2 and is provided with longitudinal slots or grooves, 10, adapted to register with the notches or slots 5 to receive a key, 11. This key is a flat plate of a thickness which will permit it to just enter and pass through the slots 5 and engage the slots or grooves 10 so that when the key is turned the key-pipe and switch plate will be turned therewith. The key is constructed with a body or handle portion, 12, and a stem, 13, and its side edges, at about the junction of the stem and body portions, are provided with notches, 14. When the key is inserted, these notches

14 will coincide with the notches 5 and, consequently, when the key is rotated the notches in its edges will engage the ring or collar 7 and withdrawal of the key is then prevented. The parts are so arranged that the key can be withdrawn or inserted only when the switch plate is in what I term the zero position, that is, with the ignition circuits inactive. The removal of the key, therefore, necessarily renders the igniters inoperative. A blank flat instrument cannot be used to operate the switch plate because if it is wide enough to engage the slots in the key-pipe it will be too wide to rotate in the central circular opening 4 of the bearing 2. The switch plate is provided in its edge with a recess, 15, which is adapted to be engaged by a lug or head, 16, carried by a spring, 17, in order to hold the plate in the zero position.

Upon the back face of the disk 8 is an insulating plate, 18, which covers the entire face of the disk except a segment, 19, constituting a contact member. The disk also carries a central spring stud, 20, which is rigidly secured in and projects rearwardly from the metallic body of the disk and is adapted to enter and bear against the inner face of a tubular binding post or terminal, 21. In order to limit the movement of the switch, I provide radial projections or stops, 22, on the edge of the disk which are adapted to impinge against some fixed part of the device and thereby arrest the rotation. A terminal plate, 23, of insulating material, is arranged in rear of the switch plate and the tubular terminal 21 is secured rigidly in this terminal plate at the center of the same. Above the central terminal, the terminal plate carries two terminals, 24, 25, which consist of binding posts and contact springs, 26, mounted on the inner ends of the posts and bearing against the face of the switch plate. In order to protect the parts from dust or other extraneous matter which might injuriously affect the electrical contacts, a rim or band, 27, is fitted to the main supporting plate 1 and has an edge crimped over the edge of the terminal plate, as clearly shown in Fig. 2, to inclose and hold said plate.

To secure the device in position, I employ a number of retaining bolts which are inserted through the frame or dashboard of the vehicle and the main supporting plate. In Fig. 2 I have shown the preferred arrangement, the bearing 2 of the main supporting plate being inserted through the dashboard, 28, or other part of the vehicle body, and a face plate or escutcheon, 29, being placed over the projecting end of the said bearing and against the part through which it projects. This face plate and the terminal plate are constructed with openings which are caused to register with the bores

of the collars or tubes 3 on the main supporting plate, and similar openings are also formed in the dashboard, as will be readily understood. The said collars or tubes 3 are internally threaded and are engaged by headed bolts, 30, inserted in their rear ends through the terminal plate and similar bolts, 31, inserted in their opposite ends through the face plate and the dashboard. By turning up these bolts, the terminal plate will be clamped against the main supporting plate and the said supporting plate and the face plate will be clamped against the dashboard or the body of the vehicle. It will be noted that by withdrawing the front bolts 31, the main plate, switch plate and terminal plate may be removed in an assembled relation and unnecessary disturbance of the parts is avoided. The construction, furthermore, permits the operating parts to be adjusted at the factory and shipped in an assembled condition so that the device may be secured in position on the vehicle by an unskilled person without disturbing the adjustment. The contact springs bearing against the switch plate tend to hold said plate in its proper position in the main supporting plate so that it may be properly engaged by the key and will not drop from the said main plate during transportation. In order to further aid in maintaining this relation of the two parts, I provide the central terminal with a small head or boss, 32, which bears against the switch plate at the center of the same, as shown in Fig. 2. The holding spring 17, which holds the switch plate in its zero position, has its ends secured to the upper collars or tubes and arches between the same over the edge of the switching disk. The resiliency of the spring thus throws the lug 16 carried thereby into engagement with the recess in the edge of the disk and will consequently hold the same in the zero position against jarring or other accident but will yield readily to permit movement of the switch after the key is inserted.

For the purposes of illustration, I have shown a magneto generator, 34, which has a main and an auxiliary winding, the main winding, 35, being connected to a contact piece, 36, at the end of the armature core, while the end of the winding is connected to a conducting sleeve, 37, surrounding and insulated from the contact piece 36. The auxiliary winding, 38, is a continuation of the main winding and its end is grounded through a metallic part of the supporting or inclosing frame. The conducting sleeve, 37, has one member of an interrupter, 39, secured on its outer end, the other member of said interrupter being connected to and carried by the contact piece 36 by means of a spindle, 40, screwed into the same. A cap, 41, covers the interrupter and

carries a spring contact, 42, on its inner side which bears against the end of the spindle 40 while a spring, 43, carried by a post, 44, bears against the outer side of the cap 41. 5 This post 44 is connected by a conductor, 45, to the post 24 on the terminal plate 23, and is also connected by a conductor, 46, to the brush of a distributor, 47, the blades or posts of the distributor being connected respectively, with the movable electrodes of the 10 sparking plugs, 48. The stationary electrodes of the plugs are formed by the metallic bodies of the plugs or the engine and, consequently, form grounded points in the 15 sparking circuit.

The central post or terminal, 21, is grounded through the metallic mass of the engine and the terminal 25 is connected by a suitable conductor with a battery, 49, from 20 which a conductor, 50, leads to a primary coil, 51, whose opposite end is grounded through an interrupter, 51^a. From the secondary coil, 52, a conductor, 52^a, leads to the movable member of a distributor, 53, while 25 from the stationary members of said distributor, conductors, 54, lead to a second set of sparking plugs, 55. The secondary is grounded at 52^b.

The battery will form an arc in one of the 30 sparking plugs 55 when the battery circuit is closed, the particular plug being determined by the distributor which is driven by the engine and is so adjusted relatively thereto as to send the current to the plug in that cylinder which is at full compression. In the magneto, when the contacts of the 35 interrupter are together, the current generated will expend its greatest strength in the circuit of the main winding. When the 40 said contacts separate the full strength of the current will be sent over the auxiliary winding circuit through the distributor to the sparking plugs, but if the segment 19 be brought into contact with the spring on 45 the terminal 24, the current will be short-circuited from the distributor over the terminal 21 and the grounded connections. Consequently, with the switch in the zero 50 position illustrated in Fig. 1, the segment 19 is in electrical contact with the terminal 24 and the magneto is grounded while the battery circuit is broken. If it be desired 55 to work under the magneto current, the switch plate is turned to the left so as to carry the segment to one side, as indicated in Fig. 8, in which position the segment will be out of contact with terminals 24 and 25, the result being that the sparking circuit of the magneto will be again established 60 and the battery circuit will remain broken. Should it be desired to work under the battery current, the segment is brought into 65 the position shown in Fig. 9, in which it will be in contact with both terminals so that the battery circuit will be established and the

magneto will be grounded. When it is desired to use the vehicle, the driver inserts the key 11 and with it turns the switch plate 8 to the position shown in Fig. 8, or that shown in Fig. 9 accordingly as it is desired 70 to work with the magneto or the battery current. The engine is then started in the usual manner and the vehicle will be propelled.

When the trip has been completed or for any other reason the vehicle is stopped, the switch plate is turned to the zero position and the key is removed. The driver may then leave the machine without any fear of its being used in his absence provided he 75 retains the key in his possession, because the battery circuit will be broken and the 80 sparking circuit of the magneto will be grounded. Consequently, attempts to start the engine will fail as no ignition will follow such efforts.

In order that each switch may have its individual key, so that only the possessor of such key may operate the motor, the key and its tube may be provided with a plurality of coacting wards, in the manner common in locks, and as will be fully understood by those skilled in the art. Such a modification is indicated in Fig. 12.

Having thus fully described my invention, 95 what I claim is:—

1. The combination of a terminal plate having a central tubular binding post, a contact carried by said plate to one side of said post, a switch plate having a central 100 stud adapted to enter and electrically engage the said tubular post and having a contact surface arranged to bear against the contact carried by the terminal plate, and means for actuating the switch plate. 105

2. The combination of a terminal plate of insulating material, a hollow post secured centrally therein, other posts secured in the terminal plate and carrying contact springs, a disk of conducting material having an overhanging segment adapted to bear upon the said contact springs, an insulating plate covering the entire face of the disk except the overhanging segment, a stud secured centrally in the disk and projecting therefrom through the said insulating plate to engage the hollow post in the terminal plate, and means for rotating the disk. 110 115

3. The combination of a supporting plate having rearwardly projecting tubes and a 120 central forwardly projecting bearing, a switch plate journaled in the said bearing, a terminal plate arranged in rear of the switch plate, and securing bolts inserted through the terminal plate into the tubes of 125 the supporting plate to secure all the parts together.

4. The combination of a supporting plate having rearwardly projecting tubes and a 130 central forwardly projecting bearing adapt-

ed to pass through a fixed support, a face plate fitted on the end of said bearing against the fixed support, a switch plate journaled in the said bearing, a terminal plate arranged in rear of the switch plate, fastening bolts inserted through the terminal plate into the rearwardly projecting tubes of the main plate, and other fastening

bolts inserted through the face plate into said tubes.

In testimony whereof I hereunto affix my signature in the presence of two witnesses.

OTTO H. H. HEINS.
